FUEL CONTROL MECHANISM

Milton E. Chandler, New Britain, Conn., assignor
to Chandler-Evans Corporation, a corporation
of Delaware

Application July 22, 1942, Serial No. 451,874

14 Claims. (Cl. 123—140)

1

My invention relates to fuel control mechanisms.

It has among its objects to provide an improved control mechanism for controlling the fuel supplied through injectors to the cylinders of internal combustion engines. A further object of my invention is to provide such an improved controlling mechanism especially adapted to use in connection with airplane engines, either of the gasoline or fuel-oil operated type. A still further object of my invention is to provide such improved controlling mechanism of the type wherein the fuel supply through the injectors to the engine cylinders varies as a function of air flow to the engine, and wherein improved cooperating mechanism is provided to control the operation of the fuel injector pump in such manner as to maintain the quantity of fuel supplied by the injectors a function of air flow under all operating conditions of the engine including enrichment under overload conditions. A still further object of my invention is to provide improved controlling mechanism for the injector pump, wherein this controlling mechanism is controlled by variations in air flow, and wherein the operation of said pump is also suitably modified by variations in the speed of the engine, while also including improved cooperating controlling means operative during the idling range. These and other objects and advantages will, however, hereinafter more fully appear.

In the accompanying drawing, I have shown for purposes of illustration one embodiment which my invention may assume in practice.

In this drawing:

Figure 1 is a diagrammatic view of my improved mechanism, and

Fig. 2 is a detail view showing the diaphragm valve of Figure 1 in a different position thereof.

In this illustrative construction, I have illustrated my invention as applied to an engine 1 including a cylinder 1a and having a suitable service shaft 2 and injector pump mechanism, generally indicated at 3, driven from the shaft 2 by a wobble cam 4 and supplying fuel to an injector 5, only one cylinder being shown in order to simplify illustration.

My improved controlling mechanism, which controls the operation of the injector pump 3, herein includes controlling mechanism responsive to variations in air flow to the engine 1. As shown, this mechanism includes an air meter 6 including a usual air venturi 7, herein of the rectangular type, and having a scoop 8 and suitable throttle means 9 between the venturi 7 and the

2

engine. In this construction, a connection 10 leads from the throat of the venturi 7 to a control valve casing 11 enclosing a diaphragm, generally indicated at D, which separates the casing into two expandable chambers 12 and 13. This connection 10 communicates with the chamber 12 below the diaphragm D, while a connection 14 leads from the scoop 8 through a chamber 15 communicating with the chamber 13 through an aneroid operated valve 16. Further, as shown, the diaphragm D comprises a central portion D' and a peripheral portion D² surrounding the portion D' and having its own periphery clamped between the peripheral portions of component casing members cooperating to form the casing 11. Moreover, note that the portion D' of this diaphragm carries usual axially disposed cooperating discs 17 and a ring 18 of larger diameter than these discs and has a coiled spring 19 biasing the ring 18 and the enclosed central portion D' of the diaphragm into the raised position shown in Figure 1, wherein the ring 18 is pressed against an annular series of stops 20 depending from the upper member of the casing 11. The stops 20 are spaced so that the same pressure acts on the entire upper surface of diaphragm D. As shown, a coiled spring 21, lighter than the spring 19, acts on said upper member as an abutment and is also disposed centrally with and acts upon the upper face of the discs 17. On the opposite face of the discs 17 from the spring 21 is a depending button 22 attached to the adjacent face of a suitable small diaphragm 23 which is suitably attached to the lower casing member around the edge of an annular chamber 24. This diaphragm 23 and valve member 22 are normally slightly raised by fluid pressure in chamber 24, to provide communication beneath the diaphragm 23 between this annular chamber 24 and an axial discharge or drain passage 25, and the button 22 rises and falls as necessary to control the escape of fluid from chamber 24, as hereinafter described. Note here also that connection between the chambers 12 and 13 on opposite sides 45 of the diaphragm D is established by passages 26 and 27 having communication between the same controlled by a suitable valve 28 forming a part of a usual manual "rich" mechanism, not shown. The total air pressure differential between the scoop 8 and the throat of the venturi 7 is a measure of the velocity of the flowing air. This pressure differential produces a flow of air thru a secondary air passage which may be traced from scoop 8 thru connection 14, chamber 15, past valve 16 into chamber 13, connection

27, past valve 28, connection 26, chamber 12 and connection 18 to the throat of venturi 7.

In this secondary air passage, the total pressure differential between the scoop 8 and the throat of venturi 7 may be considered as being divided into two component pressure drops, one across the altitude compensating valve 16 and the other across the restriction controlled by valve 28. The pressure responsive valve 16 corrects the pressure differential acting on the diaphragm D so that it is an accurate measure of the mass of air flowing per unit time, rather than the velocity of air flow. Upon a decrease in air density, such as accompanies an increase in altitude of an aircraft, the valve 16 moves toward closed position, thereby increasing the proportion of the total fuel pressure differential which takes place across valve 16, and decreasing the proportion of the total fuel pressure differential which is effective on the diaphragm D. The pressure differential on diaphragm D is thereby corrected for the decrease in the mass of air flowing per unit time due to the decrease in density.

The valve 28 is normally in a position where a small fixed restriction connects the chambers 12 and 13. It may be manually moved from this position to one where the restriction is substantially closed. When the restriction is closed, there is no air flow thru the secondary passage 30 just traced, and hence no pressure drop thru the valve 16. Valve 16 then has no controlling effect, and the diaphragm D is then subjected to the total air pressure differential.

The pressure differential on the diaphragm D acts in a downward direction on the button 22, and thereby tends to close the outlet passage 25. The pressure differential on diaphragm 23 acts upwardly against the button 22, and thereby tends to open the outlet passage 25. Since the pressure in chamber 12 is small, being customarily measured in inches of water, while the pressure in chamber 24 is relatively large, being customarily measured in inches of mercury or pounds per square inch, it may be considered that the force acting thru diaphragm 23 on button 22 in a valve opening direction is determined by the pressure in chamber 24, disregarding the effect of variations in pressure in chamber 12. The pressure differential acting downwardly on diaphragm D, as previously described, is a measure of the mass of air entering the engine. The spring 21 assists this air pressure differential but, since this is a relatively light spring, its effect is negligible except at very low air flows. The purpose and effect of spring 21 at such low air flows is explained below.

The position of button 22 controls the pressure of fluid supplied to a fluid motor 35 which controls the displacement of the injector pump mechanism 3. The fluid is supplied by a gear pump 29, whose outlet pressure is controlled by conventional relief valve 30. The fluid may be the lubricating oil of the engine, and the pump 29 may be the usual oil pump. Most of the oil discharged by pump 29 passes thru a conduit 32, but a portion of the oil passes thru a restriction 31 into a conduit 33 and thence thru chamber 24 and the outlet controlled by the position of button 22 into a drain 25, which may be connected to a suitable reservoir or to the inlet of pump 29.

The fluid motor 35 includes a cylinder in which a piston 36 is movable. The fluid under pressure is supplied to the cylinder from a conduit 34 connected to conduit 33. The pressure in conduit 33

and hence the pressure in the cylinder of motor 35 is controlled by the button 22.

Movement of the piston 36 is utilized to control the pump 3. As shown, the piston 36 is pivotally connected through a suitable slotted connection 37 to the upper end of a link 38, pivoted at its lower end at 39, and also pivotally connected between its ends at 40 to a longitudinally adjustable rod 41 controlling the position of adjustment of a valve member 42 in the injector pump 3. In the illustrative construction, this valve member 42 is reciprocable in a fuel inlet chamber 43 in the injector pump casing and reciprocably mounted on the front ends of spring pressed plungers 44 operated by the wobble cam 4, a coiled spring 45 normally biasing said valve member to the left. Herein, this valve member cooperates in its different longitudinal positions to vary the closing time of T-shaped inlet passageways 46 in the plungers 44 in such manner as to vary the amount of fuel supplied to these plungers from a usual fuel pump 47 to fuel inlet 47a and chamber 43, check valves 48 and relief ports 49 communicating with relief passages 50 being also provided.

As a result of the control of the adjustment of the position of the piston 36 in accordance with variations in the air flow to the engine and the adjustment of the valve 42 by the piston 36, it will be apparent that the quantity of fuel supplied from the inlet 47a to each injector 5 will vary as a function of air flow. Further, it will be noted that when the air flow increases sufficiently to overcome the spring 19 and increase the effective area of the diaphragm D, the pressure in pipe 23 will then be additionally built up in such manner as thereby to additionally actuate the piston 36, i. e. even further, and thereby enrich the mixture as required under such conditions while maintaining the total fuel flow a function of air flow.

Cooperating with the mechanism above described and operating to enable the above control to be influenced by variations in engine speed, improved cooperating controlling mechanism is also provided. A ball governor 51, carried on a suitable engine service shaft, which may be the shaft 2 or a suitable shaft driven therefrom, is connected to a depending link 52 pivoted at 53 and connected through a cross link 54 near its upper end to the lower end of the link 38. As a result of this connection, while the rod 41 will be operated by the piston 36 as heretofore described to adjust the valve 42, the adjustment of the latter will obviously be modified by the action of the ball governor on the link 52, the governor moving the lower pivot 39 of the link 38 in such manner as thereby to enable the speed of the engine to modify the effect of the air control and accordingly enable the mechanism to operate satisfactorily under widely varying conditions.

Under idling conditions, the quantity of air flowing thru the venturi 7 is quite small relative to the dimensions of the venturi. At such times, it has been found that the pressure differential between the chambers 12 and 13 is not an accurate measure of the quantity of air flowing thru the venturi. I have therefore provided the spring 21 which acts downwardly on the central portion D' of the diaphragm D. At normal air flows, the force of spring 21 is so small as compared to the force due to the pressure differential acting on the diaphragm that its effect is negligible. At low air flows, however, the effect of spring 21 on the diaphragm is large as compared to the effect of

the pressure differential. The spring 21 then causes the establishment of a pressure in conduit 33 which is larger than that required to cause the injector mechanism to supply a quantity of fuel proportionate to the air flow.

Cooperating with the above described controlling mechanism is also further cooperating controlling mechanism modifying the operation of the injector pump during the idling range. As shown, this mechanism includes a cam 55 carried on the throttle shaft 56 and cooperating with an adjustable member 57 carried on the lower end of the depending link 52. As shown, the latter link is biased toward the cam by a spring 58 and also carries an adjustable stop 59 engageable with a portion 59a on the engine and which cooperates with the member 57 in determining the limits of movement of the link 52 by the cam 55. Thus, when the throttle shaft 56 is adjusted into idling position, the above control mechanism automatically decreases the fuel delivered by the injector pump 3 to the quantity desired to effect idling operation.

It may be stated that the function of spring 21 is to transfer control of the fuel injector mechanism from the diaphragm D to the throttle during conditions of low air flow. Such conditions occur only when the throttle is within a range of positions adjacent its closed position, usually termed the idling range. The cam 55 is so designed that it is effective to control the injector mechanism only when the throttle is within this range of positions. Under such conditions, the spring 21 is effective to maintain a substantially constant pressure in conduit 33, so that the position of piston 26 is substantially constant and the effective control of the fuel supply is provided by the throttle operated cam 55.

In the operation of the complete mechanism, in normal operation the central portion D' of the diaphragm D will so control the valve member 22 and diaphragm 23 as to maintain the pressure in the pipe 33 a function of air flow. Consequently, the piston 36 through its connected linkage will so adjust the valve 42 automatically as to maintain the fuel flow from the fuel inlet 41a to the several plungers 44 also a function of air flow. Further, it will be apparent that as the engine speed varies, the ball governor 51 will modify the above control as necessary to automatically compensate for variations in engine speed, while, during idling, the manual adjustment of the throttle shaft 56 will effect the desired manual adjustment during operation in the idling range. As the air flow to the engine increases, however, the normally functioning portion D' of the diaphragm D will be automatically increased in area, by the addition of the peripheral portion D² thereto, as above described, in such manner as further substantially to build up the pressure in the pipe 33, and, accordingly, through the piston 36 and the linkage connecting the latter to the valve member 42, automatically further increase the quantity of fuel delivered by the several injectors to the several cylinders, in such manner as thereby substantially to enrich the mixture while maintaining the enrichment also a function of air flow.

It will be understood that while, for illustrative purposes, I have shown only one complete injector delivering to a single cylinder, a series of cylinders and injectors is provided, with each injector and cylinder successively supplied with a suitable charge of fuel through the action of the wobble cam 4. Further, it will be understood that while I contemplate the use of my improved mechanism

in connection with airplane engines having usual ignition mechanism, my improved controlling mechanism is equally well adapted to use in any Diesel type engine, which, as usual, has no such ignition mechanism and depends upon the heat of compression to ignite the charge.

While I have herein specifically described one embodiment which my invention may assume in practice, it will be understood that this has been chosen for purposes of illustration, and that the invention may be modified and embodied in other forms without departing from its spirit or the scope of the appended claims.

What I claim as new and desire to secure by Letters Patent is:

1. In a fuel control mechanism for internal combustion engines, an air conduit, control means responsive to variations in the quantity of air flowing through said conduit, hydraulic control mechanism controlled by said controlling means, fuel injector mechanism including an injector pump having a valve opened and closed during each cycle of operation of said pump, means controlled by said hydraulic control mechanism for varying the time of closure of said valve to vary the delivery of said pump as a function of air flow, and means controlled by the engine throttle for modifying the closing time of said valve.
2. In a fuel control mechanism for internal combustion engines, an air conduit, control means responsive to variations in the quantity of air flowing through said conduit, hydraulic control mechanism controlled by said control means, fuel injector mechanism including an injector pump having a valve opened and closed during each cycle of operation of said pump, means controlled by said hydraulic control mechanism for varying the time of closure of said valve to vary the delivery of said pump as a function of air flow, and means controlled by engine speed for modifying the closing time of said valve.
3. In a fuel control mechanism, an air conduit, control means responsive to variations in the quantity of air flowing through said conduit, hydraulic control mechanism including a cylinder and a piston therein reversely adjusted by said controlling means as a function of air flow, fuel injector mechanism including an injector pump having a valve opened and closed during each cycle of operation of said pump, linkage adjustable by said piston to control the time of closure of said valve to vary the delivery of said pump as a function of air flow, and throttle operated means for adjusting said linkage to automatically vary the operation of said valve and the delivery of the pump during idling.
4. In a fuel control mechanism, an air conduit, control means responsive to variations in the quantity of air flowing through said conduit, hydraulic control mechanism including a cylinder and a piston therein reversely adjusted by said controlling means as a function of air flow, fuel injector mechanism including an injector pump having a valve opened and closed during each cycle of operation of said pump, linkage adjustable by said piston to control the time of closure of said valve to vary the delivery of said pump as a function of air flow, and engine speed operated means for adjusting said linkage to modify the closing time of said valve in accordance with engine speed.
5. In a fuel supply system for an internal combustion engine, a conduit for air flowing to said engine for combustion purposes, means associated with said conduit for producing two unequal pres-

sures whose difference is a measure of the quantity of air flowing therethru, throttle means for controlling the flow of air thru said conduit, fuel injector mechanism including a plurality of reciprocating pumps for supplying fuel directly to the cylinders of said engine, means for controlling the fuel displacement per stroke of said pumps, means responsive to the difference of said two unequal air pressures including a flexible diaphragm, means attached to said diaphragm for operating said fuel displacement controlling means and effective to increase said displacement in response to an increase of said difference of air pressures, spring means biasing said diaphragm in a direction to increase said fuel output, said spring means being effective when said difference of air pressures is small to operate said diaphragm in a displacement increasing direction, and means operative as an incident to movement of said throttle means into a range of positions adjacent said closed position to reduce the displacement of said pumps regardless of the position of said diaphragm.

6. A fuel supply system for a multiple cylinder internal combustion engine, comprising a plurality of reciprocating injector pumps for supplying fuel to the cylinders of said engine, means for controlling the fuel displacement per stroke of said pumps, fluid motor means including an expandible chamber having a movable wall for operating said capacity control means, valve means for controlling the pressure in said chamber, a passage for air flowing to said engine for combustion purposes, means responsive to the rate of flow of air thru said passage for controlling said valve means, throttle means for controlling the flow of air thru said passage, and means effective when said throttle means is in a predetermined range of positions to move said displacement control means concurrently therewith and independently of said motor means.

7. A fuel supply system for an internal combustion engine, comprising injector pump mechanism for supplying fuel to said engine, means for controlling the capacity of said pump mechanism, fluid motor means, a floating lever, means connecting said capacity control means and said motor means to spaced points on said lever, a passage for air flowing to said engine for combustion purposes, means responsive to the rate of flow of air thru said passage for controlling said motor means, throttle means for controlling the flow of air thru said passage, and means connecting said throttle means to another point on said lever, so that said capacity control means may be positioned thereby independently of said motor means.

8. A fuel supply system for an internal combustion engine, comprising injector pump mechanism for supplying fuel to said engine, means for controlling the capacity of said pump mechanism, fluid motor means, a floating lever, means connecting said capacity control means and said motor means to spaced points on said lever, a passage for air flowing to said engine for combustion purposes, means responsive to the rate of flow of air thru said passage for controlling said motor means, throttle means for controlling the flow of air thru said passage, and means operative to connect said throttle means to another point on said lever when said throttle means is in a range of positions near its closed position, so that said capacity control means is then po-

sitioned by said throttle means independently of said motor means.

9. A fuel supply system for an internal combustion engine, comprising injector pump mechanism for supplying fuel to said engine, means for controlling the capacity of said pump mechanism, fluid motor means, a floating lever, means connecting said capacity control means and said motor means to spaced points on said lever, a passage for air flowing to said engine for combustion purposes, means responsive to the rate of flow of air thru said passage for controlling said motor means, throttle means for controlling the flow of air thru said passage, cam means connected to said throttle means for concurrent movement therewith, and follower means for said cam means for transmitting motion to another point on said lever, said cam and follower means being effective to move said lever when said throttle means is in a range of positions adjacent its closed position, so that said capacity control means is then positioned by said throttle means independently of said motor means.

10. A fuel supply system for an internal combustion engine, comprising injector pump mechanism for supplying fuel to said engine, means for controlling the capacity of said pump mechanism, fluid motor means, a floating lever, means connecting said capacity control means to an intermediate point on said lever, means connecting said motor means to one end of said lever, a passage for air flowing to said engine for combustion purposes, means responsive to the rate of flow of air thru said passage for controlling said motor means, throttle means for controlling the flow of air thru said passage, a second lever pivoted at one end and connected by a link to the other end of said floating lever, means biasing said second lever in a direction to increase the capacity of said pump mechanism, stop means for limiting the movement of said second lever by said biasing means, means responsive to the speed of said engine for moving said second lever against said biasing means, and cam means connected to said throttle means for moving said second lever against said biasing means when said throttle means is in a range of positions adjacent its closed position.

11. A fuel supply system for an internal combustion engine, comprising injector pump mechanism for supplying fuel to said engine, means for controlling the capacity of said pump mechanism, fluid motor means, a floating lever, means connecting said capacity control means and said motor means to spaced points on said lever, a passage for air flowing to said engine for combustion purposes, means responsive to the rate of flow of air thru said passage for controlling said motor means, and means responsive to the speed of said engine for positioning another point on said lever and thereby moving said capacity control means independently of the said motor means.

12. A fuel supply system for an internal combustion engine, comprising pump mechanism for supplying fuel to said engine, means for varying the capacity of said pump mechanism, a floating lever, a connection between said capacity varying means and a central point on said lever, fluid motor means for positioning one end of said lever, means responsive to the power output of said engine for controlling said fluid motor means, and means responsive to the speed of said engine for positioning the opposite end of said lever.

13. A fuel supply system for an internal combustion engine, comprising pump mechanism for supplying fuel to said engine, means for varying the capacity of said pump mechanism, a floating lever, a connection between said capacity varying means and a central point on said lever, fluid motor means for positioning one end of said lever, means responsive to the power output of said engine for controlling said fluid motor means, manually operable means for positioning the other end of said lever, and means responsive to the speed of said engine associated with said other end of said lever and effective to position said other end when the speed exceeds a predetermined value regardless of said manually operable means.

14. A fuel supply system for an internal combustion engine, comprising pump mechanism for supplying fuel to said engine, means for varying the capacity of said pump mechanism, float-

20

ing lever means, a connection between said capacity varying means and a central point on said lever means, fluid motor means for positioning one end of said lever means, means responsive to the power output of said engine for controlling said fluid motor means, a manually operable element positioned adjacent the other end of said lever means, spring means biasing said other end into engagement with said element so that said other end is positioned by said element, means responsive to the speed of said engine and associated with said other end of said lever means and effective when said speed exceeds a predetermined value to move said other end of said lever means out of engagement with said manually operable element so that the position of said other end is then determined by said speed responsive means and said spring means.

MILTON E. CHANDLER.
